UNITED STATES PATENT OFFICE.

GEORGE R. WYMAN, OF EAST WALPOLE, MASSACHUSETTS, ASSIGNOR TO
F. W. BIRD & SON, OF EAST WALPOLE, MASSACHUSETTS, A FIRM.

DESIGN FOR A NAIL CAP-PLATE.

No. 38,352.

Specification for Design.

Patented Dec. 11, 1906.

Application filed August 14, 1905. Serial No. 274,235. Term of patent 14 years.

To all whom it may concern:

Be it known that I, GEORGE R. WYMAN, a citizen of the United States, residing at East Walpole, in the county of Norfolk and State of Massachusetts, have invented a new, original, and ornamental Design for Nail Cap-Plates, of which the following is a specification, reference being had to the accompanying drawing, forming part thereof.

The figure is a perspective view of a nail cap-plate, showing my new design.

I claim—

The ornamental design for a nail cap-plate as shown.

GEORGE R. WYMAN.
